UNITED STATES PATENT OFFICE.

GEORGE C. CHERBONNIER, OF ST. LOUIS, MISSOURI, ASSIGNEE TO AMERICAN CAR AND FOUNDRY COMPANY, OF ST. LOUIS, MISSOURI, A CORPORATION OF NEW JERSEY.

DOOR-OPERATING MECHANISM.

1,109,614.

Specification of Letters Patent.

Patented Sept. 1, 1914.

Application filed April 9, 1913. Serial No. 759,999.

To all whom it may concern:

Be it known that I, GEORGE C. CHERBONNIER, residing at St. Louis, Missouri, and being a citizen of the United States, have 5 invented certain new and useful Improvements in Door-Operating Mechanism, of which the following is a full, clear, and exact description, such as will enable others skilled in the art to which it appertains 10 to make and to use the same, reference being had to the accompanying drawings, which illustrate the preferred form of the invention, though it is to be understood that the invention is not limited to the 15 exact details of construction shown and described, as it is obvious that various modifications thereof will occur to persons skilled in the art.

In said drawings: Figure 1 represents 20 in section a partial plan view, the section being taken on line 1—1 of Fig. 2, showing the outer ends of two cross-bearers, two creeping winding shafts resting upon the outer ends of the cross-bearers, or supported thereby as shown at the right-hand 25 end of the shaft, shown at the left of Fig. 1, by a bracket or gusset plate secured to one of the cross-bearers. In addition, Fig. 1 shows fragmentary portions of dumping 30 doors with the operating mechanism, hereinafter described, in position. Fig. 2 is a transverse, sectional view, the section being taken on line 2—2 of Fig. 1, and shows the door closed with the latch, hereinafter described, released and the winding shaft in 35 position to support the door, while Fig. 3 shows the winding shaft in its outermost position and held in said outermost position by the pivoted gravity latch hereinafter referred to, so as to be out of the path of 40 movement of the door. Figs. 4 and 5 are, respectively elevational and plan views of a bracket hereinafter referred to.

The figures of the drawings show only 45 such parts of a dumping car as are necessary to illustrate the invention forming the subject-matter of this application. The remaining portions of the car may be of any preferred type of construction with which 50 the operating mechanism hereinafter described will operate.

While in the drawings there is illustrated a center sill, a part of the vertical side wall,

cross-bearers and parts of doors which, when closed, occupy a horizontal position, 55 as shown in Fig. 2, it is to be understood that the invention is not limited specifically to that particular type of car, as it is evident that the mechanism shown will operate equally as well when applied to a 60 "center dump" car or a "side dump" car, in which the door or doors occupy an oblique position when closed, hence I do not wish to be limited to the particular type of car to which the mechanism herein 65 described is attached.

The object of the invention is to provide simple economical and durable means possessing the elements of positiveness of action and affording a positive lock for the 70 shaft with attachments to the several doors so disposed as to automatically release the shaft lock when the doors rise to their closed position.

The invention provides a creeping shaft 75 which, as shown, is located above the floor level of the car, thereby not only increasing the door opening but simplifies the construction and cheapens the application thereof to the car, means being provided 80 to keep the shaft out of the path of movement of the door during closing movement of the door, while provision is made to prevent lodgment of the load in position to interfere with the positive operation of 85 the door-operating mechanism. Means are also provided to insure movement of the shaft out of the path of the door and its appurtenances when it is desired to dump the load and, when the shaft is moved to 90 its released position, said shaft is automatically locked and held in locked position (which is the outer-most position, as shown in Fig. 3) until the door rises in 95 its closing movement, when the door-supporting hook or bracket automatically releases the pivot gravity latch which engages the shaft, at such time as it is desired to commence movement of the shaft from its outermost position, as shown in 100 Fig. 3, to its innermost position, as shown in Fig. 2, in which innermost position the shaft serves as a support for the door through the supporting bracket on the door.

The object of the invention is to provide

means which may be assembled by unskilled workmen and which do not require great exactness of fit.

Referring specifically to the parts: A indicates one of the center sills of a car which may be duplicated on the opposite side of the longitudinal central line of the car, B is the sill cover plate, C is the outer side wall, D—D are crossbearers which, as shown in Figs. 2 and 3, project laterally from the center sills and extend, as shown in Figs. 2 and 3, under the inwardly extending portion C' of the shedding surface of the side wall C, by which shedding incline the operating mechanism hereinafter referred to is protected.

Connected with the side walls C and cross-bearer D are stakes E, which may be of pressed metal as shown or of any desirable form, which stakes are preferably connected with the side wall and the outer ends of the cross-bearers by rivets or electric welding, as may be described.

Connected with the sills A are brackets F carrying pintles G, on which are secured hinged straps or loops H, which are riveted or otherwise secured to the door and serve as supporting means for the hinge-edge portion of the door in all of its positions.

Connected with the outer or normally free end of the door is a bracket 1, which is adapted to ride over the supporting shaft which bracket is preferably formed of angle shape, as shown, and is provided with a smooth horizontal lower face 2. This bracket, as shown, is connected by direct rivet connection with the outermost portion of the door and preferably projects beyond the door.

Supported and riding on the outer end portions of the cross-bearers D are winding shafts 3, which are free to rotate and which are also free to creep or travel transversely, for the purpose hereinafter described.

Connected with the wall portion C' at one end and with the stakes E at their opposite ends are a series of shaft-guards 4 which, as shown, are provided with oppositely bent end portions 5 and 6, the portions 5 being inclined to correspond with the inclination of the wall portion C', and the portion 6 extending at right angles to the body portion of the guard to adapt it for engagement with the posts E by direct rivet connection. These guards serve the double function of stiffening the shedding incline of the wall and also to prevent accidental displacement of the shaft 3.

Connected with the stakes E and suitably supported thereby are short shafts 8, which serve as supports for gravity latches 9, which latches are adapted to rock on the shafts 8 between the position shown in Figs. 2 and 3. Excessive upward thrust of the latches 9 is prevented by angular-shaped

stops or plates 12, which are riveted, as shown in Figs. 2 and 3, to the inclined wall portion C', the stops being provided to prevent accidental displacement of the latches beyond their normally operable positions, in which positions the latches may drop by gravity to engage with the shaft 3.

It will be noted that the lifting chain or cable 13 in lifting the door is wound on the shaft 3 by movement of the shaft 3 in a clockwise direction, and the unwinding of the shaft in a contra-clockwise direction will tend to move the shaft outwardly from the position shown in Fig. 2 to the position shown in Fig. 3, thus carrying the shaft beyond the nose portion 14 of the gravity latch 9 and into a recess 15 formed in said gravity latch, so that the shaft will occupy a position between the nose 14 and the stop 16 formed on said latch, at which time the weight of the latch will automatically cause the latch to engage the winding shaft and hold it in its outermost position, so that the shaft is out of the path of movement of the door and its appurtenances during closing movement of said door.

In the claims "door" in the phrase—out of the path of movement of the door—is used in its comprehensive sense of including a door and a door-supporting hook or bracket, which latter is adapted to lock over the winding shaft to support the door in its closed position.

As will be noted in Fig. 1, there are two shaft portions employed which are independently operable, so that only such bank of doors may be operated as will be within the strength of the person manipulating same, or within the power furnished for that purpose, and due to the fact that two shafts are thus employed it becomes necessary to provide a support for the right-hand end portion of the shaft shown at the left-hand side of Fig. 1. To accomplish this a gusset 20 is provided, which is formed with a vertical flange adapted to rest against the web of the contiguous cross-bearer D and be secured by suitable rivet connection, as shown, with the stake E, thereby affording a rigid support for the otherwise unsupported end of said shaft.

The operation is as follows: Assuming the door to be in its open position, as shown in Fig. 3, the gravity latch 9 is in position to embrace the shaft 3, so that when the said shaft is wound in a clockwise direction the door will be lifted, carrying with it the bracket 1, before indicated, and during the lifting movement of the door the weight of the latch 9 will be sufficient to hold the shaft in its outermost position, but when the door is lifted high enough the bracket 1 will engage the under face of the nose 14 of the latch, thereby lifting the latch on its pivot, as shown in Fig. 2, whereupon continued ro-

tation of the shaft will cause the shaft to leave its outermost position, shown in Fig. 3, and be drawn to the position shown in Fig. 2, in which latter position the shaft 5 rests under the face 2 of the bracket 1, and the load incident to the weight of the door and contents of the car is transferred from the winding chain 13 to the supporting bracket 1, and thus to the winding shaft, 10 which now serves as a support for the doors, the bracket 1 resting on the shaft until a contra-clockwise movement of the shaft will retract it from its position under said bracket, whereupon the weight of the load 15 will automatically cause the door to drop and dump the load.

When the door is closed it will be noted that the roughened collar 22 rests upon the roughened bracket 21, which is secured to 20 one of the diaphragms D. The bracket 21 is shown in dotted lines in Figs. 2 and 3 and is shown in plan in Fig. 1 secured to the left-hand diaphragm under the collar 22. The collar 22 being of greater diameter 25 than the shaft 3, it is evident that the weight of the load will force the collar downwardly into engagement with the top surface of the bracket, so as to insure positive engagement therewith in the opening movement of the 30 door, thereby insuring positive release of the shaft 3 from under the door-supporting brackets 1. But one bracket 21 and collar 22 are shown, but it is evident that as many of each as may be required will be used.

35 What I claim is—

1. In a door operating device, the combination comprising a door hinged near one edge thereof, a transversely movable winding shaft supported above the plane of the 40 opposite edge of said door when the door is closed, means connecting the door and shaft, means for locking the shaft in one position, and a trip on the door adapted to release the locking means.

45 2. In a door operating device, the combination comprising a door hinged near one edge thereof, a transversely movable winding shaft supported above the plane of the opposite edge of said door when the 50 door is closed, means connecting the door and shaft, means for locking the shaft in one position, and a supporting hook carried by the door adapted to release said shaft locking means.

55 3. In a door operating device, the combination comprising a door hinged near one edge thereof, cross bearers, a transversely movable winding shaft supported on the upper face of said cross bearers above the 60 plane of the opposite edge of said door when the door is closed, means connecting the door and shaft, and automatically operable means for locking the shaft in position on said cross bearer.

65 4. In a door operating device, the combi-

nation comprising a door hinged near one edge thereof, a transversely movable winding shaft supported above the plane of the opposite edge of said door when the door is closed, means connecting the door and shaft, and an automatically operable latch 70 for locking the shaft out of the path of movement of said door and its attachments.

5. In a door operating device, the combination comprising a door hinged near one 75 edge thereof, a transversely movable winding shaft supported above the plane of the opposite edge of said door when the door is closed, means connecting the door and shaft, and a latch mounted in position to 80 engage said shaft when the door is open and to release the shaft when the door is closing.

6. In a door operating device, the combination comprising a door hinged near one 85 edge thereof, a transversely movable winding shaft supported above the plane of the opposite edge of said door when the door is closed, means connecting the door and shaft, and a gravity latch adapted to lock said 90 shaft in position out of the path of movement of the door.

7. In a door operating device, the combination comprising a door hinged near one edge thereof, a transversely movable wind- 95 ing shaft supported above the plane of the opposite edge of said door when the door is closed, means connecting the door and shaft adapted to lift the door on rotation of the shaft and to move the shaft transversely 100 toward the door and a rigid door support adapted to engage said shaft.

8. In a door operating device, the combination comprising a door hinged near one edge thereof, a transversely movable wind- 105 ing shaft supported in proximity to the opposite edge of said door when the door is closed, means connecting the door and shaft, said means being adapted to move the shaft transversely when the door is 110 closed, means adapted to lock the shaft in position and a door-supporting bracket adapted to release the shaft to permit such transverse movement.

9. In a door operating device, the combi- 115 nation comprising a door hinged near one edge thereof, a transversely movable winding shaft movable toward and from the opposite edge of said door, means connecting the door and shaft, means for locking the 120 shaft in one position, and a support carried by the door adapted to release said shaft locking means.

10. In a door operating device, the combination comprising a door hinged near one 125 edge thereof, a transversely movable winding shaft supported near the opposite edge of said door, cross bearers supporting said shaft, means connecting the door and shaft adapted to lift the door on rotation of the 130

shaft and to move the shaft transversely toward the door, a latch adapted to engage said shaft in one position above said cross bearer, and a rigid door support adapted 5 to engage said shaft.

11. In a door operating device, the combination comprising a door hinged near one edge thereof, a transversely movable winding shaft supported in position near the 10 opposite edge of said door when the door is closed, means connecting the door and shaft, said means being adapted to move

the shaft transversely when the door is closed, means for locking the shaft when the door is open, and a door-supporting 15 bracket adapted to release the shaft to permit such transverse movement.

In witness whereof I have hereunto set my hand in the presence of two witnesses.

GEORGE C. CHERBONNIER.

Witnesses:

OSCAR HOCHBERG,

WILLIAM V. MORRISON.
